UNITED STATES PATENT OFFICE.

ALFRED S. MUNGER, OF BROOKLYN, NEW YORK.

LIQUID-HYDROCARBON BURNER.

SPECIFICATION forming part of Letters Patent No. 252,618, dated January 24, 1882.

Application filed March 22, 1881. (No model.)

To all whom it may concern:

Be it known that I, ALFRED S. MUNGER, of Brooklyn, in the county of Kings and State of New York, have invented an Improvement in 5 Liquid-Hydrocarbon Burners, of which the following is a specification.

This invention comprises a novel combination of parts, whereby is provided a burner for burning naphtha and other like light hydrocarbon oils, which has the merit of providing for an unusually rapid and effective heating without vaporization of the hydrocarbon oil immediately preceding its exit from the tip at which it is ignited, the flame resulting from said ignition being automatically regulated as concerns the inflow of the heated hydrocarbon oil to the tip, and also capable of regulation as concerns the quantity of atmospheric air admitted to the burner during combustion.

20 Figure 1 is a vertical sectional view, and Fig. 2 a plan view, of an apparatus embracing my said invention.

A is the tip, screwed upon the tubular connection B, which communicates by a passage, 25 a, with the annular chamber C. The said chamber has its outer walls composed of a thick casting, A'; and its inner walls of a thin wrought-metal tube, B', the object being to have the outer walls of said chamber of such thickness, 30 and mass of metal as to render the transmission of heat therethrough extremely slow and also small in quantity, while the inner wall, B', is of such character as to render the transmission of heat through the said inner wall very 35 rapid, facile, and in great quantity. Inasmuch as the inner wall, B', is itself of annular or cylindric form, in order to give the requisite annular shape to the chamber C, it follows that the said tube constitutes a circular passage 40 open at both ends, and in the construction and operation of the apparatus the said tube is placed above and substantially axially coincident with the burner A.

In the tubular connection B is provided a 45 suitable valve, D, by which, when required, the interior passage of the said connection B may be closed or may be diminished to any required extent, either to diminish the available cross-section of said interior of the connection B or 50 to entirely close the same to shut off communication between the tip A and the annular chamber C.

At that side of the casting A' opposite the passage a, and at the lower end of the annular chamber C, is an inlet-pipe, E, through which 55 the hydrocarbon is admitted to the said annular chamber C from any suitable source of supply, said source of supply being preferably elevated to a degree sufficient to insure the automatic inflow of the hydrocarbon through the 60 inlet-pipe E to the annular chamber C, as aforesaid.

The upper portion of the burner A is provided with an external screw-thread, upon which is screwed an internal threaded disk, G, 65 in such manner that by turning the said disk in one direction it will be moved upward to diminish the space for the passage of air between the tip A and the tubular passage formed by the tube or inner walls, B', hereinbefore described, so that by moving the said disk G up or down the inflow of air to the flame may be regulated at will.

It will be observed that the passage a connects with the annular chamber C at the top 75 of the latter, while the inflow-pipe E connects with the said chamber at the bottom thereof.

The operation of the invention is as follows: The liquid naphtha or other liquid hydrocarbon flows into the chamber C, filling the same, and 80 passing over into and downward from the passage a, through the hollow interior of the connection B, and thence to the burner A, and out at the upper end or top thereof, where it is ignited, so that the flame and hot products of combustion pass up into the tubular passage above the same, and finally out at the top of said tubular passage, where they can be utilized for any of the purposes to which the flame and hot products of combustion are applicable. During 85 the transmission through the said tubular passage the heat is readily transmitted through the extremely thin walls B' of the annular chamber C, and thereby raises the temperature of the liquid hydrocarbon which flows through 90 the said annular chamber, as just described, to a degree at which the said hydrocarbon will be most readily ignited and most effectively burned when it issues from the burner A, as hereinbefore explained, so that while the flame and hot products of combustion are caused to 95 act rapidly and effectively upon the hydrocarbon supplied to the burner A the extremely thick walls A', of cast-iron or other compara-

tively poor heat-transmitting substance, effectively preclude the loss of heat by communication from said outer walls. By this means a most effective and economical heating of the hydrocarbon is secured, and as a result an unusually intense and smokeless flame when the said hydrocarbon is consumed at the top of the burner. Furthermore, the inlet E being at the bottom of the annular chamber C, while the 5 passage a communicates with the said chamber C at the top thereof, it follows that as the hydrocarbon is expanded in the chamber C a back-pressure against the inlet E is automatically exerted by reason of such expansion of the liquid hydrocarbon within the chamber, so 10 that the higher the heat within the said chamber C the more the inflow from the pipe E is hindered; and inasmuch as a less quantity of hydrocarbon is required at a high heat than 15 at a low heat, it follows that an automatical regulation of the inflow of the hydrocarbon with reference to the requirements of the burner A is secured.

As hereinbefore explained, the admission of 20 atmospheric air to the tip of the burner is readily regulated by the disk G. In starting the apparatus, however, it is desirable that the burner A should be heated above ordinary temperatures, in order that the hydrocarbon 25 issuing at its tip may readily ignite. To this end there is provided beneath the said burner A a pan or receptacle, H, which, for conven-

ience, I designate a "flash-pan." Into this pan I pour a small quantity of the liquid hydrocarbon and ignite the same, whereupon it flashes 35 up into a momentary but intense flame, which impinges on the burner A and the adjacent portions of the connection B to an extent sufficient to heat the same, and also any portion of liquid hydrocarbon contained therein, to a degree sufficient to insure the rapid ignition of the said hydrocarbon at the top of the burner when it is required to put the apparatus in operation.

What I claim as my invention is—

An apparatus for burning naphtha and like light hydrocarbon oils, composed of the externally-threaded burner A, the annular chamber C, having thick outer walls of cast metal and thin inner walls of wrought metal, the passage 40 a, connecting with the said chamber at its top, the inlet E, connecting with the said chamber at its bottom, and the internally-threaded disk G, the burner and the disk being placed coincident with the passage through the thin internal walls of the chamber C, and the whole 45 being constructed, combined, and arranged substantially as and for the purpose herein set forth.

ALFRED S. MUNGER.
